Primary Examiner — Shannon W Morgan*Assistant Examiner* — Keith Frank(74) *Attorney, Agent, or Firm* — Sheridan Ross P.C.(57) **CLAIM**

The ornamental design for a jar, as shown and described.

DESCRIPTION

FIG. 1 is a perspective view of a jar according to a first embodiment of the claimed design;

FIG. 2 is a front elevation view of the jar of FIG. 1;

FIG. 3 is a rear elevation view of the jar of FIG. 1;

FIG. 4 is a right elevation view of the jar of FIG. 1;

FIG. 5 is a left elevation view of the jar of FIG. 1;

FIG. 6 is a top plan view of the jar of FIG. 1;

FIG. 7 is a bottom plan view of the jar of FIG. 1;

FIG. 8 is a perspective view of a jar according to a second embodiment of the claimed design;

FIG. 9 is a front elevation view of the jar of FIG. 8;

FIG. 10 is a rear elevation view of the jar of FIG. 8;

FIG. 11 is a right elevation view of the jar of FIG. 8;

FIG. 12 is a left elevation view of the jar of FIG. 8;

FIG. 13 is a top plan view of the jar of FIG. 8; and,

FIG. 14 is a bottom plan view of the jar of FIG. 8.

The broken lines in the figures are for the purposes of illustrating portions of the jar or environmental structure and form no part of the claimed design.
